CLAIM

The ornamental design for a hinged intake cover for a boat hull, as shown and described.

DESCRIPTION

FIG. 1 is a perspective view of a hinged intake cover for a boat hull showing our new design;
FIG. 2 is a top plan view thereof;
FIG. 3 is a bottom plan view thereof;
FIG. 4 is a left side elevation view thereof;
FIG. 5 is a right side elevation view thereof;
FIG. 6 is a front elevation view thereof;
FIG. 7 is a rear elevation view thereof;
FIG. 8 is a left side cut-away view thereof;
FIG. 9 is a perspective view thereof shown in an open configuration with the pin removed;
FIG. 10 is a top plan view thereof shown in the open configuration with the pin removed;
FIG. 11 is a bottom plan view thereof shown in an open configuration with the pin removed;
FIG. 12 is a left side elevation view thereof shown in an open configuration with the pin removed;
FIG. 13 is a right side elevation view thereof shown in an open configuration with the pin removed;
FIG. 14 is a front elevation view thereof shown in an open configuration with the pin removed; and,
FIG. 15 is a rear elevation view thereof shown in an open configuration with the pin removed.
